J. V. STEWART.
RAILWAY FROG.
APPLICATION FILED JAN. 5, 1912.

1,074,331.

Patented Sept. 30, 1913.

UNITED STATES PATENT OFFICE.

JOHN V. STEWART, OF JOHNSTOWN, PENNSYLVANIA, ASSIGNOR TO THE LORAIN STEEL COMPANY, OF JOHNSTOWN, PENNSYLVANIA, A CORPORATION OF PENNSYLVANIA.

RAILWAY-FROG.

1,074,331.

Specification of Letters Patent. Patented Sept. 30, 1913.

Application filed January 5, 1912. Serial No. 669,624.

To all whom it may concern:

Be it known that I, JOHN V. STEWART, a citizen of the United States, residing at Johnstown, in the county of Cambria and 5 State of Pennsylvania, have invented a new and useful Railway-Frog, of which the following is a specification.

My invention relates to railway frogs employed in the construction of railway tracks 10 and turnouts, and more particularly relates to the construction of railway frogs having frog points or frog blocks with wearing surfaces formed of an alloy of manganese steel.

15 One object of my invention is to provide a railway frog of simplified construction in which the number of parts forming the frog construction is lessened or reduced.

Another object of the invention is to provide 20 a railway frog structure having novel means whereby the use of separate filler blocks is avoided, the rigidity of the frog structure is thereby increased, the life of the wearing parts of the frog is lengthened, 25 and a frog of greater strength is obtained.

A further object of this invention is to provide 30 a railway frog structure in which the amount of machining necessary in constructing the frog is lessened and reduced to a minimum and a frog structure formed entirely of manganese steel is obtained.

Other objects of my invention will appear as is more fully described hereinafter.

Referring to the accompanying drawings 35 forming part of this specification, Figure 1 is a plan showing a frog structure constructed and arranged in accordance with my invention. Fig. 2 is a plan on a larger scale showing the integrally formed manganese steel frog point casting. Fig. 3 is 40 a plan of a chock used in forming my improved frog structure. Fig. 4 is a transverse section on the line IV—IV of Fig. 1 showing the manner in which the chock is 45 secured in position between the wing rails of the frog structure. Fig. 5 is a transverse section taken on the line V—V of Fig. 1 showing the wing rails and frog point in assembled relation. Figs. 6, 7 and 8 are 50 similar transverse sections taken respectively on the lines VI—VI, VII—VII, and VIII—VIII of Fig. 1. Fig. 9 is an end elevation of the frog point on the line IX—IX of Fig. 1.

55 In the drawings, the numeral 2 design-

nates the frog point which, as shown, is formed integrally of a manganese steel casting. The point 2 has side portions 3 which are machined so as to snugly fit between the opposite faces on the inclined under side of 60 the head and the upper inclined face of the flanges of the wing rails.

The frog point 2 is provided with grooves 4, 4, on its upper face which extend at opposite angles to its longitudinal axis and 65 merge at the toe or front end of the frog point. The heel or rear end of the frog point is bifurcated and the cross section of these bifurcated portions 5, 5, has the same contour in cross section as the track 70 rails to which they are secured when the frog is in use. The under surface of the frog point has cored recesses formed therein to lessen the weight of the casting.

Secured to the frog point by bolts 6, 7, 75 8, 9 and 10, are the wing rails 11 of the frog, these wing rails being bent in the usual manner and being formed of rolled manganese steel. Registering openings or holes are provided in the web of the wing rails 80 and in the cast frog point through which these bolts extend in securing the parts together. A chock 12 is secured between the wing rails in front of the toe of the frog point by means of the bolt 13. Bolt holes 85 are spaced at suitable intervals are provided in the web of the wing rails and in the web portion of the rear end of the frog point through which bolts extend in securing the splice bars thereto by which the frog is attached to the track rails of a railway track 90 to which the frog is applied for use.

The advantages of my invention will be 95 apparent to those skilled in the art. By employing a manganese steel casting to form the frog point and by employing rolled manganese steel rails to form the wing rails of the frog structure, a frog having integral manganese steel wearing surfaces is provided, the necessity of using manganese steel inserts is avoided and the difficulties met in securing and maintaining such inserts in place are overcome.

By forming the frog in one piece and machining the side edges thereof to fit between the adjacent faces of the head and flange portions of the wing rails, the use of 105 filler blocks is avoided, the number of pieces necessary in forming the frog structure is lessened, and the amount of machining nec- 110

essary in forming a built-up railway frog is reduced. The wing rails are rigidly secured in close contact with the engaging surfaces of the integrally formed frog point, 5 and a railway frog structure of greatly increased strength is afforded.

Modifications in the construction and arrangement of the parts may be made without departing from my invention. The size and 10 shape of the cored openings in the frog point may be varied and other changes may be made within the scope of my invention as defined in the appended claims.

I claim:—

15 1. A railway frog comprising in combination an integrally formed manganese-steel frog point, wing rails formed of manganese-steel, said frog point having integral side portions in interfitting engagement with the 20 sides of the wing rails, and means whereby the wing rails and frog point are secured in assembled relation, the rear end of the frog point being bifurcated and the bifurcated portions extending rearwardly beyond the 25 ends of the wing rails and having the cross sectional contour of the track rails to which the frog structure is attached when in use.

2. A railway frog comprising in combination an integrally formed manganese-steel 30 frog point, wing rails formed of manganese-steel, said frog point having integral side portions in interfitting engagement with the sides of the wing rails, and means whereby the wing rails are secured directly to the 35 frog point, the rear of the frog point being bifurcated and the bifurcated portions ex-

tending rearwardly beyond the ends of the wing rails and having the cross sectional contour of the track rails to which the frog structure is attached when in use.

40

3. A railway frog comprising in combination an integrally formed manganese-steel frog point, wing rails formed of rolled manganese-steel and extending rearwardly beyond the ends of the wing rails, said frog 45 point having integral side portions in interfitting engagement with the sides of the wing rails, and means whereby the wing rails and frog point are secured in assembled relation, the ends of the wing rails and 50 frog point having the contour of and abutting the ends of the track rails to which the frog structure is secured when in use.

4. A railway frog comprising in combination an integrally formed manganese-steel frog point, wing rails formed of rolled manganese-steel, and extending rearwardly beyond the ends of the wing rails, said frog point having integral side portions in interfitting engagement with the sides of the 60 wing rails, and means whereby the wing rails are secured directly to the frog point, the ends of the wing rails and frog point having the contour of and abutting the ends of the track rails to which the frog structure 65 is secured when in use.

In testimony whereof, I have hereunto set my hand.

JOHN V. STEWART.
